UNITED STATES PATENT OFFICE.

JOSEPH J. KITTEL, OF DRESDEN, SAXONY, GERMANY.

DESIGN FOR A LAMP-GLOBE.

SPECIFICATION forming part of Design No. 15,566, dated November 18, 1884.

Application filed September 10, 1884. Term of patent 7 years.

To all whom it may concern:

Be it known that I, JOSEPH J. KITTEL, residing at Dresden, Saxony, German Empire, have invented and produced a new and original Design for Gas and Lamp Globes, of which the following specification is a full, clear, and exact description, reference being had to the accompanying drawings, forming part of this specification.

10 Figure 1 represents a perspective view of my newly-designed gas and lamp globe. Fig. 2 is a horizontal section on line $x-x$, Fig. 3; Fig. 3, a vertical section on line $y-y$, Fig. 2.

This invention relates to a new configuration of a globe to be used for gas and lamps. 15 The globe is made of square shape, having four straight sides, a , with rounded upper and

lower edges. Above the sides a the globe is bulged upward to form a convex top, b , having a central circular opening. At the bottom of sides a the globe is bulged downward to form a convex base, c , having a downwardly-extending flange, d , as shown. At each of the upright edges, between sides a , a sunken elliptical panel, e , is shown, having an elliptical center piece, f .

I claim as my design—

The design for a globe having straight sides a , convex top and bottom, and panels at the upright corners, as described and shown.

JOSEPH J. KITTEL. [L. S.]
